UNITED STATES PATENT OFFICE.

ARTHUR AUGUST SEMENDINGER, OF NEW YORK, N. Y.

FLY PAPER HOLDER AND TRAP.

1,159,718.

Specification of Letters Patent.

Patented Nov. 9, 1915.

Application filed November 4, 1914. Serial No. 870,278.

To all whom it may concern:

Be it known that I, ARTHUR A. SEMENDINGER, a citizen of the United States, residing at New York, in the county of New York, State of New York, have invented certain new and useful Improvements in Fly Paper Holders and Traps; and I do hereby declare the following to be a full, clear, and exact description of the invention such as will enable others skilled in the art to which it appertains to make and use the same.

This invention relates to improvement in fly traps.

The principal objects of the invention is to provide a simple and novel device for supporting sticky fly paper in such a manner that the flies are attracted within the device and in attempting to leave the same stick to the paper.

Another object is to provide a device of this character which will support a plurality of sheets of sticky fly paper in such a manner that the flies can be caught either outside or inside of the trap.

A still further object is to provide a simple device of this character and one which is effective in use and which can be conveniently placed without danger of contact by persons or danger of the gum dripping onto the floor or articles in a room.

Other objects and advantages will be apparent from the following description when taken in connection with the accompanying drawings.

In the drawings: Figure 1 is an elevation of a trap made in accordance with my invention. Fig. 2 is a plan view. Fig. 3 is a horizontal section on the line 4—4 of Fig. 1. Fig. 4 is a vertical longitudinal sectional view on the line 3—3 of Fig. 1.

Referring particularly to the accompanying drawing, 10 and 11 represent a pair of clips, each of which comprises a pair of flat plates 12 of a length equal to the width of the ordinary sheet of sticky fly paper. Each of the plates is formed with a plurality of struck up and round tongues 13 which are disposed in vertical alinement and received vertically therethrough the depending arms 14 of a wire yoke 15. This yoke is less in length than the sheet of fly paper, for a purpose which will appear hereinafter.

Engaged around the arm 14 and bearing with its opposite ends against the plates 12 is a coiled spring 16 which normally locks

the plates to bring the longer edges, at one side in abutting relation. The lower ends of each of the arms 14 extends below the clip and is in the form of a hook 17 and supports one end of a drip tray 18. The intermediate portion of the yoke 15 is formed with a loop or eye 19 for engagement with a hook for attachment of a string to suspend the device. A substantially S-shaped hook member 20 has one end engaged in the loop 19 and the other end depending between the clevis and carrying a suitable bait 21 which may be a piece of felt or other suitable substance covered with molasses, dipped in a saturate solution of sugar or other substance which will attract the flies to the trap.

In preparing the trap for use, four sheets of sticky fly paper are necessary, these sheets being arranged in pairs, each pair being arranged back to back. The opposite ends of the sheets are clamped between the jaws of the clevis 10 and 11 and placed so that the pairs are bowed outwardly in opposite directions. This is readily accomplished for the reason that the distance between the clips is considerably less than the length of the sheets of fly paper. When the paper sheets have been so placed, the bait is placed on the hook and the hook engaged with the eye 19 and caused to depend between the sticky surfaces of the inner sheets. Thus is formed an inclosure, the side walls of which are sticky, and flies or other flying insects attracted by the bait and flying up between the inner sheets of paper will come in contact therewith and be caught. The outer surfaces of the outer sheets will also catch the flies as in the ordinary use of the sticky fly paper. The tray 18 is sufficiently large to catch the drippings from the sheets held by the clips. The drippings in the tray also serve to catch flies or other insects.

What is claimed is:

1. A fly trap comprising a yoke, clips carried by the arms of the yoke, said clips being spaced a distance less than the length of the ordinary sheet of sticky fly paper, said clips being adapted for clamping the ends of a plurality of sheets of sticky fly paper so that said sheets will bow outwardly away from each other, a bait holding device carried by the yoke and depending between the sheets of paper and a drip pan suspended below the paper.
2. A fly trap comprising a yoke having depending arms, spring clips carried by the

arms, a plurality of sheets of sticky fly paper having their ends held by the clips, said paper sheets being arranged in pairs back to back to each pair bowing outwardly, away from the other pair, and a bait suspending device disposed between the gum surfaces of the inner sheets.

Copies of this patent may be obtained for five cents each, by addressing the "Commissioner of Patents, Washington, D. C."

In testimony whereof I affix my signature in the presence of two witnesses.

ARTHUR AUGUST SEMENDINGER.
